UNITED STATES PATENT OFFICE.

PLEASANT A. LILLY, OF IRVINE, KENTUCKY.

INSTRUMENT AND MEDICINE CASE.

SPECIFICATION forming part of Letters Patent No. 416,790, dated December 10, 1889.

Application filed July 13, 1889. Serial No. 317,438. (No model.)

To all whom it may concern:

Be it known that I, PLEASANT A. LILLY, a citizen of the United States, residing at Irvine, in the county of Estill, State of Kentucky, have invented certain new and useful Improvements in Instrument and Medicine Cases, of which the following is a specification, reference being had therein to the accompanying drawings.

10 This invention has relation to an improvement in physicians' or surgeons' instrument and medicine cases, the main objects of the invention being to provide a case in which the greatest amount of space is utilized within 15 the smallest compass, and to secure the instruments, medicine-vials, &c., as firmly and snugly as possible.

Other objects and advantages of the invention will appear in the following description, 20 and the novel features thereof will be particularly pointed out in the claims.

Referring to the drawings, Figure 1 is a plan of my invention, showing the case open, one side turned upward, and the instruments, 25 vials, &c., in position; and Fig. 2 is an enlarged vertical section on the line $x-x$ of Fig. 1, having portions broken away to show the construction.

Like letters of reference indicate like parts 30 in both the figures of the drawings.

The bottom A of the case has the rigid end walls A', central partition A², and the compartment A³, which is an extension of said partition, and is adapted to receive the capsule-box M, which has the strap M' to readily withdraw the box. Along the sides of the 35 central partition are the loops a, formed of one or more pieces of leather or other material for the reception of the medicine-vials.

40 In the spaces between the large loops are the small loops a', which are adapted to receive the small vials shown, or the small vials may be held in place without the loops by the retaining force of the large vials within the 45 space between two adjacent large vials. The recesses a² in the central partition are adapted to receive and secure from injury the needles of the hypodermic syringe by entirely concealing the tubes of the needles.

50 The side B of the case is padded on its inner surface with velvet, chamois-skin, or other soft material to prevent any abrasion of the instruments. The series of loops B^x B^x B^x are intended for the reception of the instru-

ments—such as catheters, tongue-depressors, 55 forceps, lancets, grooved directors, probes, spatulae, scissors, thermometers, bistouries, and other instruments useful in emergencies. There is also a cushion B', in which needles 60 may be carried without danger of loss. The ends of the catheters and other delicate instruments may be covered with chamois-skin, if desired, to reduce still further the danger of abrasion. The flaps B² turn down over the instruments and prevent contact with any 65 other part of the case and injury by moisture of the hands in the act of removing the vials or otherwise. The opposite side C of the case has the pocket C' on its inner surface, said pocket being adapted to receive 70 powders, silk, &c.

The top D and the fastening-flap D' complete the case.

Any suitable fastening device may be employed to secure the flap of the top against 75 the adjacent side of the case when closed.

Having thus described my invention, what I claim is—

1. In an instrument-case, a rigid central partition having recesses, as a², for the reception and protection of instruments, substantially as described.

2. In an instrument-case, the combination of the case having rigid end walls and central partition, and a compartment A³, formed 85 by an extension of said partition, substantially as described.

3. An instrument-case consisting of the side C, pocket C', bottom A, end walls A', partition A², having the loops a and a', and 90 the recesses a², receptacle A³, side B, padded as described, loops B^x, cushion B', flaps B², top D, and flap D', substantially as described.

4. In an instrument-case, a case having rigid end walls and a central partition with 95 a compartment A³, which is an extension of said partition and spaced for the reception and retention of a capsule-box, one end of said compartment being formed by a portion of one of the rigid end walls of the case, substantially as described.

In testimony whereof I affix my signature in presence of two witnesses.

PLEASANT A. LILLY.

Witnesses:

JAMES W. PARK,

JOHN D. WINN.
